UNITED STATES PATENT OFFICE.

DANIEL H. WATERS, OF GRAND RAPIDS, MICHIGAN.

IMPROVED BARREL.

Specification forming part of Letters Patent No. 97,840, dated December 14, 1869.

To all whom it may concern:

Be it known that I, DANIEL H. WATERS, of Grand Rapids, in the county of Kent and State of Michigan, have invented a new and Improved Barrel; and I do hereby declare that the following is full, clear, and exact description thereof, reference being had to the accompanying drawings making part of this specification, in which—

Figure 1 is a side elevation of my improved barrel. Fig. 2 is a vertical section through one-half of the barrel, showing the manner of connecting the several parts together. Fig. 3 is a top view of the barrel with the cover removed. Fig. 4 shows a portion of the cover in section. Figs. 5 show modifications of joints which may be adopted in uniting the sections composing the barrel.

Similar letters of reference indicate corresponding parts in the several figures.

The object of this invention is to produce barrels, or cylindrical packing-boxes, of horizontal sections, bent in a cylindrical form, and united, by means of hoops and nails, in such manner as to effect substantial work, with greater facility and less expense than hitherto.

To enable others skilled in the art to understand my invention, I will describe its construction and operation.

In the accompanying drawings, A A A represent three horizontal bands or cylindrical sections, made of thin wooden sheets, and secured in their cylindrical form by lapping and nailing their edges. These sections rest one upon the other, and are of equal diameter, so that when brought together a flush surface will be presented, exteriorly and interiorly, as shown in Fig. 2. For the purpose of securing the sections together I employ hoops B B, of sufficient width to lap well over the joints, and close these joints, as shown in Fig. 2. I nail the hoops to the sections above and below their respective joints, thereby firmly uniting the sections, and forming the cylindrical body

of a barrel or box. The top and bottom pieces or heads C C' may be secured in their places in any well-known manner; but I prefer to effect this by the use of rims or hoops B', rabbeted as shown in Figs. 2 and 4, the lips of which hoops will hold the heads firmly and tightly in place when the hoops or rims are nailed to the barrel or box. If additional security is required against a parting or separating of the sections A, narrow strips of metal a may be applied externally or internally to the barrel, in a direction with the longitudinal axis thereof, and their extremities turned over the ends of the barrel, and secured in any suitable manner.

In carrying my invention into effect I do not confine myself to the number of horizontal sections A shown in the drawings, as a greater or lesser number of these sections may be employed, united by the hoops B. Nor do I confine myself to the use of the ties a, as very substantial work, which will answer a good purpose for many packing-barrels or boxes, can be produced without such strips.

I am aware that it is not new to make a box or barrel of a single piece of material, bent in proper form, and hooped to strengthen it, and I do not, therefore, claim such as my invention. Nor do I confine myself to the precise manner shown of making the joints between the horizontal sections—that is to say, of uniting the edges of the horizontal sections—as this may be done by lapping, rabbetting, tongue and grooving, as shown in Figs. 5, or by the flush abutting-joints shown in Fig. 2.

Having described my invention, what I claim as new, and desire to secure by Letters Patent, is—

As a new article of manufacture, a barrel or box, composed of horizontal sections A, united by means of hoops B, as described.

DANIEL H. WATERS.
